INK ROLLER BRAKE FOR PRINTING PRESSES

Filed May 25, 1929

UNITED STATES PATENT OFFICE

FREDERICK E. HUGHES, OF TORONTO, ONTARIO, CANADA

INK ROLLER BRAKE FOR PRINTING PRESSES

Application filed May 25, 1929. Serial No. 366,021.

The principal objects of the invention are to overcome the difficulty of unequal distribution of ink on the inking plate of printing presses and to provide a simple form of device which may be readily attached to the press and which is very reliable and positive in its operation.

The principal feature of the invention consists in the novel construction and arrangement of a brake member operatively connected with the inking roller whereby said roller is brought into contact with the fountain roll with a new point of contact at each movement of the roller between the fountain and the inking plate.

In the drawings, Figure 1 is an elevational view of a portion of a printing press showing a part of the frame, the ink reservoir, the fountain roll and the improved brake mechanism.

Figure 2 is an enlarged perspective view of the brake device.

Figure 3 is a sectional view of the brake mechanism taken on the line 3—3 of Figure 2.

The inking mechanism of certain types of printing presses has for many years been subject to a defect which many have endeavoured to overcome by various devices to check the spinning of the ink roller as it leaves the inking plate.

In the device herein shown a small cylindrical brake drum 1 is rotatably mounted on the shaft 2 of the inking roller 3 and it is preferably formed with side flanges 4 and a hole 5 therethrough. A clamp 6 is secured on the end of the shaft 2 and is provided with a spring button latch 7 which enters the hole 5 and thus causes the drum to turn with the shaft. The head of the button 7 is formed with a notch 8 in its periphery and a pin 9 secured in the clamp passes through the notch when the latch is locked to the drum and said pin holds the latch disengaged by pulling the latch outwardly and turning same so that the pin engages the underside of the head.

The drum 1 is provided with a boss 10 on its inner side which is formed with an annular groove 11 and said boss is rotatably held

in a flange ring 12, formed in half sections which is secured by the screws 13 to the boss 14 of the inking roller operating arm 15 which is a part of the standard press structure and carries the roller in its movement to and from the fountain roll 16 which is arranged on the ink font 17, said arm 15 being pivoted on the frame 18 and operated by the link rod 19.

A pair of semi-circular members 20 and 21 hinged together encircle the brake drum 1 between its flanges and the inner faces thereof are preferably provided with a suitable friction lining 22.

The hinge pin 23 connecting the members 20 and 21 extends through the hinge ends of a pair of U-shaped members 24 and 25 and hardened steel rollers 26 and 27 are mounted in said U-shaped members on the pins 28 and 29 extending transversely therethrough, the peripheries of the rollers extending beyond the faces of the U-shaped members farthest from the members 20 and 21.

A bracket 30 is rigidly mounted on the frame 18 of the press and is formed with an upwardly extending arm 31 having a curved face 32 which is concentric to the pivot 33 of the arm 15. Depressions 34 and 35 are formed at the upper and lower ends of the face 32.

The brake members 20 and 21 are each formed with a lug 20' and 21' in which are threaded the set screws 36 and 37 provided with lock nuts 38 and 39 to engage said lugs.

A compression spring 40 is arranged between the outer free ends of the brake members 20 and 21, being seated in recesses in said ends and said spring tends to force the members 20 and 21 apart so that they will not grip the drum arranged therebetween.

The set screws are adjusted so that the heads thereof engage the outward sides of the U-shaped members 24 and 25 and said members, when the rollers 26 and 27 are in engagement with the concentric face 32 of the arm 31, force the brake members 21 and 22 together to grip the brake drum to hold the ink roller from rotating. When either of the rollers 26 or 27 drop into the depression 34 and 35 the pressure against the brake mem-

bers is relieved and the spring 40 immediately spreads them apart to release the braking grip and allow the ink roller 3 to rotate.

In the operation of this device, the arm

- 5 15 swings downwardly on its pivot to bring the ink roller 3 into contact with the roll 16 and just prior to the roller 3 engaging the roll 16, the roller 27 on the U-shaped member 25 drops into the lower depression 35 on 10 the arm 31 releasing the brake and allowing the roller 3 to turn with the fountain roll. The arm 15 then swinging upward carries the roller 3 away from the roll 16 and the roller 27 is lifted out of the depression 35 15 and the brake is applied and the roller 3 is held from rotation until the arm 15 approaches the upward limit of its movement and the roller 26 of the upper U-shaped member drops into the depression 34 again releasing 20 the brake so that the ink roller 3 will rotate freely when engaged by the reciprocating ink distributor plate, which is not shown as its structure and arrangement are well known.
- 25 The rotation of the ink roller in its engagement with the inking plate is uniform and as the movement of the roller is positively arrested as the roller leaves the ink plate it is held in a fixed position till it engages the 30 slowly rotating fountain roll which turns the roller 3 only a part of a revolution. This operation thus advances the ink roller the distance of its travel in rotation with each contact with the fountain roll which ensures 35 the ink roller being brought into contact at a different point in its periphery at each stroke of the ink roller arm, consequently the ink will be applied to a different part of the roller at each stroke and a uniform distribution 40 will be effected.

- 45 The clamp member with its latch enables the releasing of the roller 3 for cleaning by simply lifting the latch and turning it and by turning the latch until the pin 9 slips into the notch 8 the brake is again in operation.

What I claim as my invention is:—

1. An ink roller brake for printing presses, comprising, an oscillating roller, means carried with said roller adapted to be operated 50 to close around the roller shaft to arrest the rotative movement thereof, and means for operating said arresting means periodically.
- 55 2. In a printing press, the combination with the oscillating inking roller, of relatively movable braking members carried with the inking roller adapted to free the inking roller at the ends of its oscillating movement and hold it from rotation during the remainder of its movement.
- 60 3. In a printing press, the combination with the frame, the inking roller and the pivotal oscillating support therefor, of relatively movable braking members carried by said oscillating roller support for holding the inking roller from rotation, and means arranged 65

on the frame adapted to operate said relatively movable members individually and to release same at the ends of the oscillating movement.

4. In a printing press, the combination 70 with the inking roller and oscillating means for carrying same, of a brake mechanism comprising an articulated member mounted on said oscillating means adapted to arrest the rotation of the inking roller, and means 75 adapted to operate and release the movable portions of said articulated brake member at the ends of the oscillating movement of the inking roller to control the rotation of said roller.

5. In a printing press, the combination 80 with the frame, the inking roller and the pivotal oscillating support therefor, of a pair of hinged braking members adapted to arrest the rotation of the inking roller, a rigid 85 bracket member having a surface concentric with the pivot of the inking roller support, and members operatively connected with said hinged braking members and engaging said concentric surface to apply the brake to arrest 90 the rotation of the inking roller.

6. In a printing press, the combination 95 with the frame, an oscillating member pivoted on the frame, and an inking roller rotatably mounted in said oscillating member, of a brake drum mounted on said inking roller, a brake member encircling said drum, a pair 100 of arms pivotally mounted and operatively connected with said brake, rollers mounted on each of said arms, a rigid bracket having a concentric surface adapted to engage said rollers and apply the brake to arrest the rotation of the inking roller, said arms releasing said brake at the upper and lower extremities 105 of the oscillating movement.

7. In a printing press, the combination 110 with the frame, an oscillating member pivoted on the frame, and an inking roller rotatably mounted in said oscillating member, of a brake drum mounted on said inking roller, a pair of brake arms hinged together and extending around said drum, a spring holding the free ends of said arms apart, a pair of members pivotally mounted on the hinge connection of said brake members, a roller 115 mounted on each of the latter members, set screws mounted in the brake members engaging the pivotal members connected thereto, and a fixed member having a concentric surface adapted to engage said rollers to operate 120 said pivotal members to force the brake members into braking engagement with the drum, said fixed member having depressions at the ends to release the brake.

8. In a printing press, the combination 125 with the frame, an oscillating member pivoted on the frame, and an inking roller rotatably mounted in said oscillating member, of a brake drum mounted on said inking roller, a clamp secured to the inking roller 130

shaft, a spring latch on said clamp engaging said brake drum to carry it with the ink roller, a brake engaging said drum, and means for operating said brake to arrest the rotation of the inking roller during the major portion of the oscillating movement and releasing it at the ends.

9. In an ink roller brake for printing presses comprising the combination with the ink fountain and the ink distributing mechanism, of an ink roller, means for carrying said roller from the ink fountain to the ink distributor, and means carried with the ink roller adapted to arrest the roller from rotation as it leaves the distributor and hold same from rotation until it approaches the ink fountain to effect the contact of the ink roller with the fountain at a different point in its circumference following each oscillating movement.

10. In a printing press, the combination with the oscillating inking roller, of relatively movable braking members comprising pivotally connected members carried with the inking roller adapted to free the inking roller at the ends of its oscillating movement and hold it from rotation during the remainder of its movement.

11. In a printing press, the combination with the frame, an oscillating member pivoted on the frame, and an inking roller rotatably mounted in said oscillating member, of a brake drum mounted on said inking roller, a pair of brake arms hinged together and extending around said drum, and supported thereby in a floating manner, and means for operating said brake arms to grip or release said brake drum during its oscillating movement.

12. In a device of the class described, in combination, a rotatable shaft mounted to oscillate bodily between two end positions, non-rotatable means normally loosely carried by said shaft, and means for tightening said first named means upon said shaft during its bodily movement between said end positions to control the rotation of said shaft.

13. In a device of the class described, in combination, a rotatable shaft mounted to oscillate bodily between two end positions, and means loosely carried by a said shaft when occupying said end positions and adapted to control the rotation thereof during its bodily movement between said end positions.

14. In a device of the class described, in combination, a rotatable shaft mounted to oscillate bodily between two end positions, means loosely carried by said shaft when occupying said end positions, and means for causing said first named means to prevent free rotation of said shaft during its bodily movement between said end positions.

15. In an inking mechanism for printing

presses or the like, which includes a fountain roller, a member to be inked, a ductor roll arranged to oscillate bodily between said fountain roller and said member and to rotate in contact therewith, and an axle for said ductor roll, a member loosely carried by said axle when said ductor roll is in contact with said fountain roller or said member to be inked and adapted to prevent rotation of said axle and ductor roll when they are in intermediate positions.

16. In an inking mechanism for printing presses or the like, which includes a fountain roller, a member to be inked, and a ductor roll mounted on a shaft for bodily oscillation between said fountain roller and said member and for rotation in contact therewith, in combination, a member loosely carried by said shaft when said ductor roll is in contact with said fountain roller or said member to be inked, and means for causing said member carried by said shaft to prevent rotation of said shaft during bodily oscillation thereof.
